Atto.

UNITED STATES PATENT OFFICE.

OTTO R. GRASS, OF CHICAGO, ILLINOIS, ASSIGNEE TO THE ORO-TONE COMPANY, OF CHICAGO, ILLINOIS, A CORPORATION OF ILLINOIS.

SOUND-CONTROL CONSTRUCTION.

Application filed February 28, 1924. Serial No. 695,882.

To all whom it may concern:

Be it known that I, OTTO R. GRASS, a citizen of the United States, residing at Chicago, in the county of Cook and State of Illinois, have invented certain new and useful Improvements in Sound-Control Construction, of which the following is a specification.

This invention relates to a new and improved sound control construction and more particularly to a method for controlling sound transmission through a phonograph tone arm or similar construction.

Numerous types of phonographs, as now produced, have no method of controlling the volume of sound transmitted from the sound amplifier chamber. The application of such volume control means involves a considerable expense and large parts where passage of sound through such a large opening is to be controlled. The control of the volume in the smaller tone arm passages may be carried out with smaller and more simple parts.

It has now become a common practice to use a phonograph tone arm and sound amplifying chambers for amplifying sound from loud speaking units operated by radio receiving apparatus. In general, this use requires the removal of the usual phonograph reproducer and the connection thereto of the loud speaking unit by some suitable coupling means. This substitution requires a certain amount of time and labor and with many forms of machines cannot be easily and quickly carried out.

It is an object of the present invention to provide volume control for a transmission of sound from a sound producer unit of any sort to a phonograph tone arm or similar structure.

It is a further object to provide a construction of this character adapted to selectively control the sound transmitted to a single tone arm or equivalent from a plurality of sound producing mechanism such as a phonograph sound box and a radio telephone loud speaker.

It is an additional object to provide a construction of this character which is composed of but few and simple parts and which is adapted for ready commercial production.

Other and further objects will appear as the description proceeds.

A preferred embodiment of the present invention is illustrated in the accompanying drawings, in which—

Figure 1 is a plan view of a tone arm with my construction fitted thereto;

Figure 2 is an elevation of Figure 1;

Figure 3 is a section taken on line 3—3 of Figure 1;

Figure 4 is a section taken on line 4—4 of Figure 1; and

Figure 5 is a perspective view of the shutter member.

The tone arm 11 may be of any usual construction and provided with a usual type of enlarged base 12 which is secured to the motor board of the phonograph. The passage in the tone arm communicates with any usual type of sound amplifying chamber. The T 13 has a portion 14 fitted into and suitably secured to the small end of the tone arm 11.

As best shown in Figure 3 the T 13 is provided with a reduced end 14 upon which is rotatably fitted a connecting member 15. The threaded stud 16 extends from a reduced end of the T through the member 15 and the latter is held in place by means of the nut 17 threaded on stud 16 and locked in position by a set screw 18. The rotation of the member 15 upon the reduced portion of the T is limited by means of the screw 19 carried by member 15 and the cooperating slot 20 cut in the portion 14 as best shown in Figure 4. As shown in this figure the portion 14 of the T is provided with the lateral opening 21 which communicates with the opening in the member 15 when that member is turned to place the sound box in the operated position.

The elbow 26 is fitted into the member 15 and is provided with a spiral groove 22 which coacts with the spring pressed ball 23 carried by the member 15. The sound box 24 is rotatably carried upon the end of the elbow 26. As indicated in broken lines in Figure 4, the rotation of the sound box is limited by the spring pressed ball 25 cooperating with the groove 26 in the elbow.

The opposite end of the T 13 is provided

with a reduced portion 27 which is adapted to receive the loud speaking unit or what is known as a phone adapter for connecting a phone unit thereto. The upper side of the T 13 is provided with the slot 28. The shutter 29 is fitted within the transverse bore of the T and is provided with the stud 30 extending through slot 28. Thus stud 30 carries the plate 31 which is pressed against the outer surface of the T by the spring 32 which latter is held in place by the head 33 of the stud. The shutter 29 is provided with wing extensions 34 and 35 which are adapted to close off the slot 28 from the bore of the T.

In the use of my device where a full volume of sound from the phonograph reproducer is desired, the shutter 29 will be placed in the position in which it is shown in Figures 1 and 3. The cross bore of the T is then in direct communication with the opening through the portion 14 of the T and with the tone arm. If it is desired to reduce the volume of sound the shutter is moved to the left by pushing the head 33 of the stud 30 to the left. Any desired portion of the opening through portion 14 of the T may thus be cut off from communication with the sound box.

If it is desired to use the tone arm and T in connection with a loud speaking unit such unit is fitted to the reduced portion 27 of the T, as indicated in broken lines in Figure 1. If it is then desired to transmit the full volume from the loud speaking unit to the tone arm 11 the shutter 29 is moved fully to the left to the dotted line position shown in Figure 3. If it is desired to modify the volume of sound transmitted from the loud speaking unit the shutter 29 may be placed in any desired intermediate position.

When using the construction in connection with the loud speaking unit, the sound box may be swung back above the tone arm, the screw 19 and slot 20 cooperating to limit this movement. The sound box, elbow and connector, as shown, are suitable for use with both zig-zag and hill-and-dale records. When the parts are in the position shown in Figures 1 and 2, zig-zag records are

played. With the parts turned in the position shown in Figure 4 in broken lines, hill-and-dale records are played.

My sound control construction is adapted to fully transmit sound from either the sound box or loud speaking unit or to modify sound transmitted from either unit. This construction readily adapts a phonograph to use as a radio phone loud speaker and thus materially increases its utility.

I have illustrated one preferred form of my invention but I contemplate such changes and modifications as come within the spirit and scope of the appended claims.

I claim:

1. A sound control construction comprising a tone arm, a T connected to said tone arm, means for connecting a sound box to one end of said T, the other end of the T being adapted for connection to a loud speaking unit, and a sliding shutter fitted into the T and adapted to selectively cut off connection from either end of the T to the tone arm.

2. A sound control construction comprising a tone arm, a T connected to said tone arm, means for connecting a sound box to one end of said T, the other end of the T being adapted for connection to a loud speaking unit, a sliding shutter fitted into the T and adapted to selectively cut off connection from either end of the T to the tone arm, and an operating member connected to the shutter and extending through a slot in the T.

3. A sound control construction comprising a tone arm, a T connected to said tone arm, means for connecting a sound box to one end of said T, the other end of the T being adapted for connection to a loud speaking unit, a sliding shutter fitted into the T and adapted to selectively cut off connection from either end of the T to the tone arm, a slot in the T, an operating member for the shutter extending through the slot, and wings on the shutter adapted to close the slot throughout the range of movement of the shutter.

Signed at Chicago, Illinois, this 26th day of February, 1924.

OTTO E. GRASS.
